UNITED STATES PATENT OFFICE.

JOHN H. HUNT, OF DAYTON, OHIO, ASSIGNOR TO THE DAYTON ENGINEERING LABORATORIES COMPANY, OF DAYTON, OHIO, A CORPORATION OF OHIO.

IGNITION SYSTEM.

Application filed April 2, 1921. Serial No. 457,890.

To all whom it may concern:

Be it known that I, JOHN H. HUNT, a citizen of the United States of America, residing at Dayton, county of Montgomery,

5 State of Ohio, have invented certain new and useful Improvements in Ignition Systems, of which the following is a full, clear, and exact description.

This invention relates to ignition systems 10 for internal-combustion engines and has among its objects the provision of spark shower ignition for engine starting and and single spark ignition for engine running, such ignition being provided for by one 15 ignition coil cooperating with a timer or a trembler. More particularly it is an object to reduce the inductance of the coil when the trembler is connected so that the trembler may be operated magnetically by 20 an ignition coil having relatively high inductance.

Other and further objects and advantages 25 of the present invention will be apparent from the following description, reference being had to the accompanying drawing, wherein a preferred embodiment of the present invention is clearly shown.

The figure of the drawing is a wiring 30 diagram of a preferred form of the invention.

In the drawing, a battery 20 grounded at 21 furnishes current for ignition through switch 22, wire 23, primary 24 of coil 25, switch contacts 26, 27, 28, wire 29, timer 30 35 grounded at 31. A condenser 32 grounded at 33 is connected in parallel with timer 30. The secondary 34 of coil 25 is grounded through battery 20, and is connected with distributor 35 for distributing sparking 40 pulses to grounded spark plugs of an engine (not shown).

The trembler circuit includes contact 40 grounded at 41 and cooperating with contact 42 mounted on armature 43 pivoted at 44. Contacts 40 and 42 are normally maintained in engagement by spring 45. A condenser 46 is connected in parallel with contacts 40, 42. Armature 43 is so located as to be magnetically attracted by coil 24 when 50 energized so as intermittently to break the

trembler circuit as will be described. Wire 47 connects armature 43 with switch contact 48. Wire 50 connects contact 49 with an intermediate turn 51 of winding 24.

As shown in the drawing the ignition 55 system is in condition for normal engine running. To provide spark shower ignition a handle 52 connected with contact 27 is moved to disconnect contacts 26, 28 and to connect contacts 48, 49. The timer 30 60 will be rendered inoperative, but a portion of primary coil 24 will be energized to attract armature 43 against the tension of spring 45 intermittently to break the trembler circuit. In this manner a series of 65 sparking impulses will be induced in rapid succession in secondary 34 to produce a shower of sparks at one of the spark plugs, depending on the status of the distributor.

Where the primary of an ignition coil has 70 sufficient turns to provide satisfactory ignition for the low engine speeds, the regular timer being used to time the coil discharge, such a coil has not been found satisfactory to operate a trembler for the spark shower 75 which is useful to enable easy starting. I have found that if the inductance of such a coil be reduced, then the coil will operate satisfactorily in conjunction with the trembler. In the preferred form of my invention, I obtain this reduction of coil inductance when the trembler is brought into operation by connecting the trembler and battery in series with a portion only of the primary turns. The number of turns employed 80 will of course vary with different coils.

While the form of mechanism herein shown and described constitutes a preferred 85 form of the embodiment of the invention, it is to be understood that other forms might be adopted, all coming within the scope of the claims which follow.

What I claim is as follows:

1. In an ignition system, the combination 95 with a current source and an ignition coil having primary and secondary windings; a timer; a trembler in magnetic relation to said coil; and means for connecting the coil, timer, and current source or for connecting 100

the trembler and current source with the coil to operate the trembler with a reduced inductance in the coil.

2. In an ignition system, the combination with a current source and an ignition coil having primary and secondary windings; a timer; a trembler in magnetic relation to said coil; and means for connecting all of the primary turns of the coil, with the timer

and current source, or for connecting the current source and trembler with a portion of the primary turns of the coil.

In testimony whereof I hereto affix my signature.

JOHN H. HUNT.
